(57) **CLAIM**

The ornamental design for an outboard motor as shown and described.

DESCRIPTION

FIG. 1 is a front perspective view of an outboard motor according to our new and ornamental design;

FIG. 2 is a rear perspective view thereof;

FIG. 3 is a side elevation view thereof;

FIG. 4 is an opposite side elevation view thereof;

FIG. 5 is a front elevation view thereof;

FIG. 6 is a rear elevation view thereof;

FIG. 7 is a top view thereof; and,

FIG. 8 is a bottom view thereof.

The broken lines illustrate portions of the outboard motor that form no part of the claimed design.

1 Claim, 6 Drawing Sheets
